UNITED STATES PATENT OFFICE.

RYOKUWAN KUSAMURA, OF KINGS COUNTY, CALIFORNIA.

MOTOR-BOAT.

1,091,355.

Specification of Letters Patent. Patented Mar. 24, 1914.

Application filed May 27, 1913. Serial No. 770,212.

To all whom it may concern:

Be it known that I, RYOKUWAN KUSAMURA, a subject of the Emperor of Japan, residing in the county of Kings, in the State of California, have invented certain new and useful Improvements in Motor-Boats, of which the following is a specification.

This invention relates to motor boats, and more particularly to the type known as pedo-motor, and has for its object the provision of a boat provided with side propeller-wheels and adapted to be propelled by pedaling, as in a bicycle.

An important object of the invention is to provide a device of this character which is so constructed that either propeller-wheel may be disconnected from the source of power simply by shifting a lever in order that the boat may be turned easily and much more quickly than could be done by means of a rudder.

Other objects and advantages such as simplicity, cheapness, efficiency, durability, ease of motion and the general improvement of the art will be clearly brought out in the following specification and illustrated in the accompanying drawings, in which:

Figure 1 is a side elevation of my improved boat, Fig. 2 is a top plan view thereof, Fig. 3 is a longitudinal sectional view, Fig. 4 is a cross sectional view through the propeller shaft, Fig. 5 is a fragmentary top plan view illustrating the means for disconnecting the power from a propeller-wheel, and Fig. 6 is a perspective view of the sliding shifting member.

Referring more particularly to the drawings, the numeral 1 designates the hull of my improved boat which comprises a bottom or floor 2, and a vertical shell or wall 3. The hull may be of any desired shape, size and material.

Rigidly mounted upon the bottom 2 and adjacent the stern of the boat is an upright support 4 upon which is secured a seat 5 which may be of a type used on bicycles and which may be adjusted vertically, if desired, to vary the height for different operators. Journaled through suitable bearings on the support 4 is a crank shaft 6 which is provided with pedals 7 and to which is secured a sprocket 8. Secured upon the bottom 2 approximately midway of the boat are upright plates 9 which are adapted to support the various portions of the motor to be described.

Journaled through the rear portion of the plates 9 is a transverse shaft 10 upon which is mounted a sprocket 11 about which is trained a chain 12 which is further trained about the sprocket 8. A fly-wheel 13 and gear-wheel 14 are also mounted upon the shaft 10, the gear 14 meshing with a gear 15 secured upon a transverse shaft 16. The shaft 16 is supported by the plates 9 and carries a gear 17 which meshes with a pinion 18 secured upon a transverse shaft 19 journaled transversely of the forward ends of the plates 9. Journaled below the shaft 19 is a similar shaft 20 which carries a pinion 21 meshing with a pinion 22 secured upon the shaft 19. This intermediate pinion 21 also meshes with a pinion 23 secured upon the propelling shaft which is indicated as a whole by the numeral 24. A pair of fly-wheels 25 are mounted upon the shaft 19 for steadyng the motion of the various shafts and gears mentioned.

The propeller shaft 24 comprises a central sleeve 26 upon which the pinion 23 is keyed, the sleeve 26 being keyed upon a short shaft 27 which extends beyond the ends of the shaft 26. Tubular shafts 28 extend through the wall 3 of the boat and carry upon their outer ends propeller-wheels 29. The propeller shafts 28 encircle the short shaft 27 and are provided upon their inner ends with clutch teeth 30 adapted to interlock with similar clutch teeth 31 formed upon the sleeve 26. It will thus be seen that the tubular shafts 28 are slidably upon the shaft 27 and through the walls 3 of the boat. In view of the fact that the tubular shafts 28 are loosely mounted upon the shaft 27, it will be obvious that as long as the clutch teeth 30 and 31 are in engagement the propeller-wheels 29 will be rotated. However, if the tubular shafts 28 should be moved outwardly a sufficient distance to disengage the clutch teeth 30 and 31, it will be seen that the propeller-wheels 29 will cease rotating. In accomplishing this I provide adjacent each side of the boat shifting members 32 which are supported by guide tracks 33 secured upon the bottom 2 of the boat. The shifting members 32 are provided with heads 34 within which are formed openings 35 to receive the tubular shafts 28. The heads 34 are provided with inclined portions 36 which engage collars 37 formed on the propeller shafts 28. Coil springs 38 surround the propeller shafts 28 and abut against the collars.

37 and the wall 3 of the boat. Each of the shifting members 32 has connected therewith a lever 39 as shown at 40, said levers being pivoted within brackets 41 secured upon the bottom of the boat. As shown in the drawings, the levers 39 are in their forward position and the propeller shafts 28 are then held in engagement with the sleeve 26 by virtue of the action of the springs 38. 10 By pulling either of the levers 39 rearwardly one of the shifting members 32 will be moved rearwardly whereupon the inclined portion 36 will engage the collar 37 thus moving the tubular shaft 28 outwardly of 15 the boat and upon the shaft 27 as a guide and against the resistance of the spring 38. Either propeller-wheel may in this manner be disconnected and rendered idle.

The ordinary steering mechanism comprises a vertical rod 42 journaled through the bottom of the boat and provided upon its upper end with a transverse rod 43 which terminates in upturned handles 44 adapted to be held by the operator at all times while 20 the boat is in motion. Beneath the bottom of the boat the rod 42 is provided with lateral extensions 45 to which are connected rearwardly extending rods 46 which are connected with a cross bar 47 formed on the 25 rudder post 48 which carries the rudder 49 and which is journaled in the bottom of the boat.

It will thus be seen that the train of gears described will cause the propeller-wheels 29 30 to rotate and drive the boat, and with great steadiness owing to the fly-wheels 13 and 25. For ordinary steering purposes the rudder 39 is sufficient but in order to turn abruptly or within a limited space the disconnection 35 of either of the propeller-wheels may be made by means of the shifting members described, thus allowing the other propeller-wheel to rotate independently and turn the boat as desired.

40 Having thus described my invention what I claim is:

1. A motor boat comprising a hull, a propeller shaft journaled transversely thereof, said shaft being provided with 45 clutch faces, propellers mounted on said shaft and provided with clutch faces engaging said first named clutch faces, means for rotating said shaft, springs for normally holding said clutch faces in engagement, and wedging means for breaking the connection of said clutch faces.

2. A motor boat comprising a hull, a propeller shaft journaled transversely therethrough, said shaft comprising a central portion provided with clutch teeth and 50 extended portions, propellers loosely mounted

ed on said extended portions and provided with clutch teeth in engagement with said first named clutch teeth, and means for breaking the engagement of either of said 65 clutches, said means comprising a slidable wedge and a lever for operating the wedge.

3. A motor boat comprising a hull, a propeller shaft journaled transversely thereof, said shaft comprising a central portion provided with clutch members and extending portions, propellers secured on sleeves loosely mounted on said extended portions, said sleeves being provided with clutch members in engagement with said first- 70 named clutch members, collars mounted on said sleeves, springs engaging said collars and said hull for maintaining said clutch members in engagement, and means for disconnecting either of said clutch members, said 75 means comprising slidable wedge members engaging said collars and levers for operating said wedges.

4. A motor boat comprising a hull, a propeller shaft journaled transversely thereof, 80 said shaft comprising a central portion provided with clutch members and extending portions, sleeves loosely mounted on said extending portions and provided with clutch members engaging said first named clutch 85 members, propellers secured on said sleeves, collars secured on said sleeves, springs engaging said collars and said hull for holding said clutch members in engagement, and means for breaking said engagement, said 90 means comprising members movable longitudinally of the hull, inclined faces on said members adapted to engage said collars, and upright levers pivoted upon said hull and pivotally connected with said members.

5. A motor boat comprising a hull, a standard mounted thereon, a seat secured upon said standard, a crank journaled through said standard and provided with 95 pedals, a sprocket secured upon said crank, a shaft, a sprocket on said shaft, a chain trained about said sprockets, a gear on said shaft, a propeller shaft, a train of gears connecting said first named shaft with said 100 propeller shaft, propellers loosely mounted on said propeller shaft, clutch members formed on said propeller shaft and on said propellers, springs for normally holding said clutch members in engagement, and wedge operated means for disconnecting 105 said clutch members.

In testimony whereof I hereto affix my signature in the presence of two witnesses.

RYOKUWAN KUSAMURA.
